UNITED STATES PATENT OFFICE.

ARVID EMANUEL KARLBERG AND MARSHALL BIDWELL SARGENT, OF OWENSBORO,
KENTUCKY, ASSIGNORS TO THE STENOTYPE COMPANY, OF INDIANAPOLIS,
INDIANA.

TYPE-WRITING MACHINE.

1,105,081.

Specification of Letters Patent.

Patented July 28, 1914.

Application filed April 7, 1914. Serial No. 830,316.

To all whom it may concern:

Be it known that we, ARVID E. KARLBERG and MARSHALL B. SARGENT, citizens of the United States, and residents of Owensboro, 5 in the county of Daviess and State of Kentucky, have invented certain new and useful Improvements in Type-Writing Machines; and we do hereby declare the following to be a full, clear, and exact description 10 of the invention, such as will enable others skilled in the art to which it appertains to make and use the same.

Our invention relates to improvements in typewriting machines and particularly to 15 ribbon mechanism therefor,—the object of the invention being to simplify and improve ribbon mechanism, to the end that its operation shall be sure and accurate, and so that it may be readily shifted either normally or 20 automatically with accuracy and without danger of derangement of or undue strain upon any of the parts.

With this object in view, the invention 25 consists in certain novel features of construction and combinations of parts as hereinafter set forth and pointed out in the claims.

In the accompanying drawings, Figure 1 30 is a longitudinal sectional view of a stenographic typewriting machine embodying the improved ribbon mechanism; Fig. 2 is a front elevation partly in section, and Fig. 3 is a view partly in plan and partly in section.

35 1 represents the main frame or casing of the machine, in the upper portion of which a platen 2 is located, and mechanism is provided for feeding a strip 3 of paper step-by-step in front of the platen. The paper feeding mechanism forms no part of the present 40 invention and a detail explanation of the same is unnecessary. It may be stated however, that the paper feeding mechanism is connected with and operated by the movements of a universal bar 4,—the latter being actuated by arms 5 of key levers 6. The type bars 7 of the machine are pivotally mounted in a notched bar 8 and connected at their lower ends with the key lever arms 5.

45 50 A transverse frame 9 is secured within the main frame or casing 1 and is provided with bearings for vertical shafts 10, 10, to which

ribbon reels 11 are secured and the inking ribbon 12 is guided from one reel to the other and between the type of the type bars 55 and the platen by means of suitable guide rollers 13.

Bevel pinions 14 are secured to the lower portions of the vertical shafts 10 and mesh with smaller bevel pinions 15 secured to 60 short shafts 16, the latter being mounted in suitable bearings 17 on the transverse frame 9. The short shafts 16 are provided with clutch members 18, 19 and the inner end 65 portions 20 of the short shafts constitute 70 bearings for a sleeve 21 mounted to slide thereon, said sleeve being provided at its respective ends with clutch teeth or members 22—23 to coöperate with the clutch members 18, 19.

A ratchet wheel 24 is made rigid with the sleeve 21 and is actuated by a dog 25, which is pivotally attached to and actuated by the universal bar 4 and is guided in its movements by the slotted upper end of a post 26 75 rigid with the frame 9. Retrograde rotation of the ratchet wheel is prevented by a dog 27 pivotally supported by the post 26.

The ratchet wheel 24 is loosely embraced by the arms 28 of a yoke 29, and this yoke 80 is also made with arms 30 hung by means of pivoted links 31 from a block 32 rigid with the frame 9. The yoke 29 is made with an operating arm 33 which passes upwardly through an elongated slot 34 in the 85 block 32 and projects above said block a sufficient distance to permit the operator to readily grasp it to shift the ratchet wheel and the clutch devices when it is desired to change the direction of feed of the inking 90 ribbon.

The block 32 is made with horizontal sockets 35 in which rods 36, 37 are longitudinally movable, springs 38, 39 being located in said sockets between the inner ends of said rods 95 and the operating arm 33 at respective sides of the latter. Slots 40 are made in the block 32 to receive pins 41 on the rods 36, 37 for guiding said rods and preventing them from turning. At their outer ends, the rods 36, 37 100 are provided with rollers 42, for a purpose hereinafter explained. The operating arm 33 is made with two notches 43 to receive a spring pressed dog 44 mounted in a hollow

boss 45 on the block 32, for retaining the operating arm and the parts which it controls from accidental displacement.

Each ribbon reel is provided with a hub 46 which depends below the reel as shown in Figs. 1 and 2. Each of these hubs is made with a recess 47 which is normally spanned by a spring actuated hinged section 48, the spring tending to open this hinged section when the ribbon shall have become exhausted from the reel, as shown at the right hand side of Fig. 3, but when the ribbon is on the reel, the hinged section 48 will be closed and held so by the ribbon, as shown at the left in Fig. 3.

During the normal operation of the mechanism, the rollers 42 of the rods 36-37, will ride on the hubs 46 of the ribbon reels, and two springs 38-39 will be under approximately the same tension, so that the ratchet wheel and clutches will remain in the positions to which they may be shifted (the spring-pressed dog 44 assisting in such retention) and so that said ratchet wheel and clutch devices may be shifted manually.

When the inking ribbon shall have become exhausted from one of the reels, the hinged section 48 of the hub 46 of this reel will be opened by the action of its spring, the roller 42 of one of the rods (36-37) will be forced by the action of one of the springs (38 or 39) in a direction to enter the now uncovered recess in the reel hub. The roller 42 on the rod (36 or 37) will first engage hub 46 at one edge of the recess and the pressure exerted against said rod by the spring (38 or 39) will cause the reel-hub to be positively moved sufficiently to insure the entrance of the roller 42 into the recess.

When one of the rods (36 or 37) is caused by its spring at one side of the operating arms 33 to move longitudinally as above described, the tension of the spring at the opposite side of said operating arm will cause the latter to be moved laterally. As the arm 33 is rigid with the swinging yoke 29, the latter will be moved when spring-pressure is applied as above described to the arm 33, and the movement of the yoke will operate to shift the ratchet wheel and alter (by means of the clutch devices) its operative relation to the respective reel gearings, thus effecting a reversal in direction of the feed of the inking ribbon.

It is apparent that when the key levers are operated, the universal bar 4 will be actuated to operate the dog 25 and thus cause motion to be transmitted (through the ratchet wheel clutch devices and gearing) to one of the ribbon reels and that when the shifting devices are operated, either manually or automatically, motion will be transmitted to the ribbon reel for moving the inking ribbon in the reverse direction.

Having fully described our invention what

we claim as new and desire to secure by Letters-Patent, is:—

1. In ribbon mechanism for typewriting machines, the combination with two ribbon reel shafts, alining shafts, and gearing between said ribbon reel shafts and said alining shafts, of a ratchet wheel between said alining shafts, clutch devices between said ratchet wheel and said alining shafts, a universal bar, key levers actuating said universal bar, a dog carried by the universal bar and engaging the ratchet wheel, and means for shifting said ratchet wheel to shift the clutch devices. 70

2. In ribbon mechanism for typewriting machines, the combination with ribbon reel shafts, alining shafts, and gearing between said alining shafts and ribbon reel shafts, of a ratchet wheel between said alining shafts, means for actuating said ratchet wheel, clutch devices between the ratchet wheel and alining shafts, a yoke embracing the ratchet wheel, springs for moving said yoke to shift the ratchet wheel and the clutch devices, and means for controlling the operation of said springs. 80

3. In ribbon mechanism for typewriting machines, the combination with a frame, ribbon reel shafts, alining shafts, and gearing between said alining shafts and the ribbon reel shafts of a ratchet between the alining shafts, means for actuating the ratchet wheel, clutch devices between the ratchet wheel and the alining shafts, a swinging yoke suspended from the frame 100 and embracing the ratchet wheel, and means for actuating said yoke to shift the ratchet wheel and the clutch devices. 95

4. In a ribbon mechanism for typewriting machines, the combination with a frame, 105 ribbon reel shafts, alining shafts, and gearing between said alining shafts and the ribbon reel shafts, of a ratchet wheel between the alining shafts, means for actuating said ratchet wheel, clutch devices between said ratchet wheel and the alining shafts, a block rigid with the frame, a swinging yoke suspended from said block and embracing the ratchet wheel, an operating arm projecting from said yoke and through a slot in said block, said block also having horizontal sockets, rods longitudinally movable in said sockets, springs between said rods and the operating rod, and means for controlling the movements of said rods to shift said yoke, 115 ratchet wheel and clutch devices. 120

5. In a ribbon mechanism for typewriting machines, the combination with a frame, a block rigid therewith, ribbon reels having recessed hubs, spring actuated sections for normally closing the recesses in the reel hubs, gearing for actuating the reels, and means for shifting the operative relation of said gearing from one reel to the other, of an operating arm movable in said block, connec- 125 130

tions between said arm and the gear shifting means, rods longitudinally movable in said block, rollers on said rods and coöperating with the reel hubs, springs in the block between said rod and the operating arm, and a spring-pressed dog carried by the block for holding the operating arm in position to which it may be shifted.

In testimony whereof, we have signed this specification in the presence of two subscribing witnesses.

ARVID EMANUEL KARLBERG,
MARSHALL BIDWELL SARGENT.
